United States Patent Office

Des. 185,568
Patented June 23, 1959

185,568

CARVING FORK OR SIMILAR ARTICLE

Emil S. Polk, Scarsdale, N.Y.

Application December 29, 1958, Serial No. 53,960

Term of patent 14 years

(Cl. D44—29)

Fig. 1

Fig. 2

Fig. 3

Fig. 4

Figure 1 is a front elevational view of a carving fork showing my new design.

Figure 2 is a side elevational view thereof as seen from the righthand portion of Figure 1.

Figure 3 is a view in elevation showing the side opposite that seen in Figure 1.

Figure 4 is a view in elevation showing the side opposite that seen in Figure 2.

I claim:

The ornamental design for a carving fork or similar article, substantially as shown.
